UNITED STATES PATENT OFFICE.

HARRY M. GOLDBERG, OF SAN FRANCISCO, CALIFORNIA, ASSIGNOR TO H. M. GOLDBERG CO., OF SAN FRANCISCO, CALIFORNIA, A PARTNERSHIP.

AWNNG FRAME.

Application filed January 31, 1925. Serial No. 5,937.

This invention relates to outdoor signs, and more particularly to an illuminated sign for attachment to a foldable awning such as is commonly used on store fronts.

5 In many cities there are restrictions as to the use of electric signs, particularly as to the extent that they may be projected from the side of the building, their height from the sidewalk, etc. Usually these restrictions do 10 not apply to signs placed upon a so-called marquise, or some permanent covering. While they likewise do not apply to signs mounted upon foldable types of awnings, I am not aware that anyone has heretofore 15 applied an electric sign to such foldable awnings so that the sign may be projected and retracted with the awning and maintained in position where it will be easily readable at all times. Frequently such awnings are let down at night when the weather is inclement, and their extending frame offers an ideal location for an electric sign.

It is the object of my invention to provide 20 a sign, especially an illuminated sign, for attachment to the frame of a foldable awning, with provision for maintaining the sign in upright position both when the awning is folded and when it is extended, so that the sign can easily be observed at all times.

30 In the accompanying drawing,

Fig. 1 shows a side elevation of an awning equipped with the present invention;

Fig. 2 shows a front elevation of the same in folded position;

35 Fig. 3 shows a perspective view of a modified arrangement of the sign and operating mechanism therefor;

Fig. 4 shows a side elevation of a different 40 type of awning from that shown in Fig. 1, also equipped with my invention;

Fig. 5 shows a side elevation of a modified form of controlling means for maintaining the sign in upright position.

The type of awning shown in Figs. 1 and 45 2 permits of vertical movement of the frame so that the awning will move downwardly when folded. In this form the awning frame consists of side arms 10 pivotally connected at their inner ends to bearings 11 50 slidable on vertical rods 12, secured to the supporting structure or wall 13. There is a connecting or cross bar 14 at the outer ends of the arms 10, and a canvas covering 15 is secured at one edge to this bar, the other 55 edge of the canvas being connected to a

roller 16 arranged in a recess 17 formed in the wall 13. When the awning is raised the canvas is wound upon the roller 16, and the cross bar 14 forms a closure for the recess, so as to conceal and protect the canvas structure. In applying my invention to the style of awning above described, I mount a rigid sign support 18 upon the cross bar 14 by means of hinges 19. To maintain the sign support in upright position at all times I 60 arrange a control rod 20 at each side of the awning, preferably above and parallel with said arms 10. The outer end of each control rod is pivotally connected to the adjacent 65 upper corner of the sign support, and the inner end of each control rod is pivoted to a sliding bearing 21, similar to bearings 11, and movable therewith on the rods 12. When the awning is extended the sign occupies a vertical position at the outer edge 70 of the awning, as shown in full lines in Fig. 1, and when the awning is folded the sign is disposed in upright position in front of the cross bar 13, as indicated in dotted lines in said figure. This sign is intended to be 75 electrically illuminated, and the control rods 20 may be made hollow, and thus serve as conduits for the electric wires.

In Fig. 3 I show an arrangement where 80 the sign is of less length than the length of the awning frame. Here the sign frame is indicated at 22, and is fixed upon a rock shaft 23 mounted in bearings on the cross bar 14. At each end of the rock shaft is a 85 rock arm 24, to which is pivotally connected a control rod 25 suitably connected at its inner end to the supporting wall.

In Fig. 4 the slidable bearings at the inner 90 ends of the side bars 10 and control rods 20 are dispensed with, and stationary lugs 26 are provided instead. The operation of the awning and sign in other respects is similar to the one above described.

In Fig. 5 I show a modified form of mechanism for controlling the position of the sign. 100 This comprises a stationary toothed quadrant 27 at the inner end of each side arm, and an oscillating toothed quadrant 28 at the outer end of each of said side arms. The sign is fixed to a cross rod 29 extending between the outer movable quadrants and the movable quadrants are rocked by means of a toothed rack 30, supported slidably in stirrups 31 fixed to the side arms. When the awning is raised from the position shown in 105 110

solid lines, the racks are moved downwardly by the stationary quadrants, and thereby act to rock the outer quadrants and keep the sign in upright position as shown in dotted lines in Fig. 5.

It will be observed that my invention may be readily attached to any of the usual forms of folding awnings, and will not in any wise interfere with the operation of the awning. As will be appreciated from Fig. 2, the sign occupies a conspicuous place when the awning is folded, and when the awning is extended the sign is projected out to a point near the edge of the sidewalk, at a low elevation. Thereby passengers in street cars and automobiles, as well as pedestrians on the opposite side of the street, are certain to have their attention directed to the sign. The controlling means shown herein is simple and inexpensive to construct, and to put in place, and serves at all times to maintain the sign in upright position and prevent the sign from swinging on its pivots under the influence of a high wind.

Various changes in the construction and arrangement of the several parts herein shown may be employed without departing from the spirit of my invention, as disclosed in the appended claims.

What I claim as new and desire to secure by Letters Patent is:

1. The combination with a foldable awning having a frame consisting of side arms pivotally connected to a suitable supporting structure, a connecting bar connected to the outer ends of the arms, of a rigid sign support arranged adjacent said connecting bar and mounted for rocking movement, and a member disposed adjacent to each side arm and extending from the supporting structure to said sign support and operatively connected to the latter to positively act upon the sign support to maintain the latter in upright position in any position of the awning.

2. The combination with a foldable awning having a frame consisting of side arms pivotally connected to a suitable supporting structure, a connecting bar at the outer ends of the arms, of a rigid sign support arranged adjacent said connecting bar for rocking movement, and control means extending parallel with the side arms and connected to the sign support at one end and to the supporting structure at the other end, whereby to maintain the sign support in upright position in either position of the awning.

3. The combination with a foldable awning having a frame consisting of side arms pivotally connected to a suitable supporting structure, a connecting bar at the outer ends of the arms, of a rigid sign support arranged adjacent said connecting bar and

mounted for rocking movement, a rod arranged above each side arm and extending parallel therewith, each of said rods being pivotally connected to the sign support and to the supporting structure for the awning, whereby the sign support will be maintained in upright position at all times.

4. The combination with an awning having a frame consisting of side arms pivotally connected to a supporting structure, a cross bar arranged at the outer ends of the arms, a flexible covering secured at one edge to said cross bar, a roller arranged in a recess on the supporting structure upon which the flexible member is adapted to be wound, said cross bar serving to close the recess when the awning is folded, of a rigid sign support hinged to the outer edge of the cross bar and a rod at each end of the awning, extending parallel with the side arms and pivotally connected at one end to the sign support, and at the other end pivoted to the supporting structure, whereby the sign support will be maintained in upright position both when the awning is extended and when it is folded.

5. The combination with an awning having a frame consisting of side arms pivotally connected to a supporting structure, a cross bar arranged at the outer ends of the arms, a flexible covering secured at one edge to said cross bar, a roller arranged in a recess on the supporting structure upon which the flexible member is adapted to be wound, said cross bar serving to close the recess when the awning is folded, of a rigid sign support hinged to the outer edge of the cross bar and a rod at each end of the awning, extending parallel with the side arms and pivotally connected at one end to the sign support, and at the other end pivoted to the supporting structure, whereby the sign support will be maintained in upright position both when the awning is extended and when it is folded, said rods being hollow and serving as conduits for electric wires, whereby the sign structure may be illuminated.

6. The combination with a foldable awning having a frame consisting of side arms slidably and pivotally connected to a suitable supporting structure, a connecting bar connected to the outer ends of the arms, of a rigid sign support swingingly connected to said connecting bar, and a rod disposed adjacent to and parallel with each side arm above the same and relatively closed thereto with each side arm slidably and pivotally connected to the supporting structure and pivotally connected at the outer end to said sign support to positively act upon the sign support to maintain the latter in upright position in any position of the awning.

HARRY M. GOLDBERG.
